UNITED STATES PATENT OFFICE

GENNADY FRENKEL, OF KINGSTON-ON-THAMES, ENGLAND

ADVERTISING OR LIKE SIGN OR DEVICE

Application filed November 19, 1928, Serial No. 320,484, and in Great Britain May 14, 1928.

This invention relates to advertising or like signs or devices adapted to be illuminated during the day by daylight admitted through an opening in the top of the device, 5 hereafter referred to as the window, as the opening may in fact be an opening or glazing, having in mind that it functions for the admission of light which is afterwards reflected to the sign characters through which 10 it is diffused.

One object of the present invention is to devise an arrangement of reflectors in a device of the kind referred to which will avoid any loss of light admitted into the device, 15 due to reflection back through the window from reflectors disposed to direct admitted light to the sign walls, and further to conserve the admitted light so that all is ultimately utilized in illuminating the sign 20 characters.

Another object is to devise a manufacture wherein the cost of production is exceedingly small as compared with present day practice.

25 A feature of constructions according to the present invention is the employment of curved reflectors for reflecting daylight admitted into the device to the sign characters.

Another feature is the employment of reflectors contiguous to the opening or window for directing downwardly into the device light reflected upwardly therein. Such reflectors used in combination with reflecting surfaces carried on the side walls virtually 30 form a trap for the admitted light and a control of the reflection within the device so that by repeated reflection all the light admitted is directed through the sign characters and none allowed to be lost by reflection back 35 through the window of the device.

Such form of construction may be considered as equivalent to that of a non-return valve because the device so constructed permits the flow of light into the device but 40 prevents the return flow through the admission opening, the exit for the light being constituted solely by the sign characters of the device or that area allotted as a ground 45 for the sign characters, as hereafter more 50 fully explained.

Preferably, an advertising device comprising reflectors contiguous to the opening, as herein described, comprises also reflectors opposite the window of the sign which either directly or through the agency of the reflectors contiguous to the opening, direct light to the sign walls carrying the sign characters.

The reflectors contiguous to the window opening may be of plane or curved form, 60 and as hereafter explained the device may be produced with the walls all integral by moulding a tube of transparent material, for instance, glass to incorporate the necessary reflecting surfaces and window opening.

In forming an advertising device suitable for the display of two advertisements at the same time in opposite directions, the device preferably includes two opposed sign walls carrying sign characters and mutually reflecting surfaces.

A preferred construction relating to the production of advertising signs having reflectors contiguous to the window as herein described, is given by way of example in the accompanying drawings.

Fig. 1 shows diagrammatically in vertical section the application of the invention to a sign made from a glass tube and including two side walls intended to carry sign characters so that a display is made simultaneously in two opposite directions;

Figs. 2 to 6 are diagrammatic, indicating the formation of the reflecting walls;

Fig. 7 shows pictorially another construction in which the reflecting walls are integral;

Fig. 8 being a section on the line VIII—VIII of Fig. 7.

Referring now to Fig. 1, the window of the device is that part of the section lying between the reference characters X—X at the top of the device, and besides the window the tube is provided with six faces indicated by the references 1 to 6, two of which, 2 and 5, are intended to bear sign characters, and the curvature of the faces varies in accordance with the angle of incidence of the incoming rays striking the respective faces, having in mind that it is desired that all the 90 95 100

received light is directed on to the faces 2 and 5. The faces 1, 6, form a border or frame to the light admission opening constituted by the window aforesaid.

5 The tube constructed as illustrated in Fig. 1 is adapted to collect and reflect rays from whatever angle they may arrive between zero and 180° and to direct the rays downwardly.

10 The light reflected upwardly by the reflecting faces 3 and 4 is returned downwards towards the sides 2 and 5 by the reflectors 6 and 1 contiguous to window X—X, at the same time the reflectors 1 and 6 are capable of receiving light emanating from low angles, i. e. from near the horizon, and of directing this low angle light downwardly into the device.

15 It will be seen, therefore, that the tube has two characteristics; it includes reflecting surfaces, viz. surfaces 1 and 6, by which at least a double reflection of the incoming light takes place to acquire the ultimate downward direction of the light to the sides, and the reflecting faces which immediately 20 downwardly direct the incoming light impinging on them.

25 The direction of incoming light is clearly indicated by the lines shown on the diagram, for instance, the line I—I shows the path of light entering from very nearly the horizon on the right hand side of the tube, the rays striking the face 6 and then reflected downwardly towards the panel 5, the line II—II indicates the path of a ray entering from immediately above the sign and striking the bottom face 4. This light is reflected on 30 to the top face 1 and then directed downwardly from that face to the opposite side face 5. The line III—III indicates the path 35 of a ray of light striking the face 5 and being reflected (downwardly) according to the ordinary law of optics to the opposite side face 2, if it does not pass through (as indicated 40 in the figure) sign characters on the side panel 5. The line IV—IV indicates the path 45 of a light ray entering from an angle towards the horizon on the left hand side of the tube striking the side face 2 and then, if not passing through, is directed across the tube and slightly downwardly towards the face 5, similarly to the ray on path III—III.

50 The path shown by the lines V—V shows the entry of light from vertically above the tube and striking the bottom face 3 which is reflected thence to the face 6 and then downwardly to the side face 2.

55 From the foregoing it will be seen that supposing the faces 2 and 5 are sign panels that all the light received from horizon to horizon is directed through the sign panels and emerges in all directions. By such an arrangement an extensive field of vision for 60 the sign is obtained and a greater brilliancy

than heretofore. At the same time dazzling is avoided.

It will be obvious that the curvature of the walls of the tube may vary in accordance with the width of the opening X—X of the tube and in accordance with the desired angle downward of the reflected light.

65 The faces 1 and 6 may provide concave reflectors as shown or they may be plane reflectors. Also the bottom reflectors 3 and 4 may be set at a smaller angle to the contiguous sides 2 and 5 respectively so that they form a re-entrant angle equal to an angle between the sides 3 and 4 shown in Fig. 1.

70 Generally speaking, it may be stated that the walls of the tube are optically constructed so as to reflect all the light entering through the opening X—X on to the side walls such as 2 and 5 of the tube.

75 If necessary the glass utilized may be a reinforced glass, e. g. a glass in which wire netting is embedded.

80 By such form of construction all the admitted light is utilized by the reflection and repeated reflection to pass through the sign walls of the device and as the sign walls themselves are reflectors, if the light does not pass through the actual characters on the sign walls it is reflected back to the characters on the other walls and not absorbed by 85 the walls.

85 The reflecting surfaces of a sign as herein described, may be made up from separate panels instead of being integrally formed and the curvature of the several surfaces may be attained by utilizing strip material. A tubular sign constructed, for instance, according to Fig. 1 may be made of corrugated or ribbed glass, and such construction attains a diffusion of the incoming light which is 90 subsequently reflected through the sign panels.

95 To give an ornamental grounding to the characters themselves, muffed or shaped glass may be employed, such as ornamental or "cathedral" glass. Alternatively, the characters may be formed in ground or frosted glass so as to give a matt effect.

100 Whatever the glass employed for producing a repeated reflection within the advertising device, or to vary the ornamental nature of the sign shown up by the illumination, the reflection of the admitted light, as herein described and claimed, results in rays of light passing through the sign characters and emerging in varying angles.

105 The invention also involves a novel method of manufacturing daylight signs which method consists in forming the tube from glass, as, for example, by blowing and converting the tube into a mirror, whereby a novel form of advertising device is produced, viz. a sign constituted by a tube of transparent material, e. g. glass, of which the walls constitute a carrier for, or are converted into, re- 110

flecting surfaces, except for the area occupied by the sign characters, and a longitudinally disposed area as a window for the admission of light, whereby the light admitted through the window is reflected within the device and is dissipated through the sign characters.

Conveniently, the characters may be formed during the formation of the tube, as for example, by blowing or moulding. To this end the mould may have an interchangeable portion carrying the sign characters so that the mould may be easily adapted for each sign to be constructed.

The conversion may be attained by an applied coating of reflecting material or metal, or by chemically forming a layer of reflecting substance. In either case the walls become the carriers for the mirrors.

Signs as herein described may be formed by mirroring the outside or the inside of the tube, preferably the outside, the mirror being translucent. Characters may be delineated by applying opaque lacquer to the outside of the tube except for the area covered by the characters, and in this way the translucent mirror will be converted into a mirror proper except for the sign character areas which would be translucent permitting the transmission of light rays.

Alternatively, the characters may be formed on the tube by sand blasting or otherwise abrading the tube.

The delineation of the sign characters may be effected by selectively modifying the translucent characteristic of the mirror to form contrasting areas delineating the signs.

Preferably, however, part of the mirrored surface is rendered opaque so that the sign characters are delineated by the diffusion of the light through them against the dark ground.

As hereafter more fully explained a tubular sign may be completed by sealing the ends of the tube against admission of light, for instance, by the use of end plates by which the sign can be supported.

Referring now to the diagrammatic Figures, 2—6, Fig. 2 shows a glass wall G in which the characters of the sign are sand blasted as indicated at C and the wall silvered to form a mirror as indicated at S except for the area covered by the characters of the sign.

A mirror may be formed by the use of a silver nitrate silvering solution or mercury amalgam or by applying metal foil, and then a transparent lacquer will be applied to prevent the mirror so formed blackening under atmospheric effects.

Alternatively, as shown in Fig. 3, the silvering may be on the outside of the wall covering it entirely, or as shown, excepting the areas over the sign characters. In this case the silvering will be covered with a backing (except where it covers the characters) usually presenting a black surface so

as to produce the greatest contrast between the grounding and the characters. Conveniently, the black grounding may be attained by applying a lacquer to the silvering coating; a transparent lacquer can be applied where the mirror covers the characters to avoid atmospheric effects.

As an alternative to forming the lettering by sand blasting, the glass itself may be frosted or matt glass, as indicated by the reference G' in Fig. 4, so that the characters C silhouetted by the grounding will have substantially the same effect as if they were sand blasted on plain glass. The mirror may be applied to the back as indicated, and as already explained with reference to Fig. 3.

Further, the characters may be obtained by etching or grinding as well known in the art.

To increase the reflection value or artistic effect of the wall, the wall may be formed from ribbed or muffed glass, as indicated in Fig. 5 by reference G'', or the glass may be of the kind known as "ornamental" or "cathedral" glass.

With a view to still further brightening the characters the glass may be thinner in the area in which the characters are formed. Conveniently, this may be attained by forming the characters on each side of the glass as indicated at C and C' in Fig. 6. Alternatively, the glass may be thicker in the area of the characters, which latter may be moulded integrally with the plate.

Any of the constructions mentioned with regard to Figs. 4, 5 and 6, may be utilized whether the silvering is either inside or outside as described with reference to Figs. 2 and 3.

In the constructions shown in Figs. 7 and 8 the advertising device comprises walls all integral with one another, and is of tubular form and "open" at the top for the admission of light through 180° from the sky.

Light will enter the open top of the device through all angles through 180° (as the sign is hung with the window in a horizontal plane, the 180° includes all the light available from the sky), and will be reflected from the backs of each of the several walls to the side walls directly or indirectly.

In stating that the advertising device is "open" at the top it does not in fact mean that there is necessarily no top wall. There is in fact a top wall of glass which as before stated may be muffed or ribbed glass, i. e. a window, thereby the advertising device is open for the admission of light. Moreover, it is not necessary for the whole of the wall to constitute an opening for light, in some positions of a sign sufficient light may be admitted even if the central part of the top wall is opaque.

The tubular design of advertising device may conveniently be formed by blowing the tube in glass, as hereinbefore explained, and

by providing end frames 7 carrying opaque walls, 8, 8, to which hooks 9 may be secured for the purpose of suspending the device from a cantilever system diagrammatically indicated at 10.

5 The characters on the two signs may be in staggered relation so that a mirrored surface is opposed to a character and vice versa.

10 Light entering the open top will strike the convex face of the top walls, the side walls and the bottom walls, which latter are joined together preferably to obtain a somewhat parabolic form for the lower portion of the device, from which the light will then be 15 transmitted either directly to the side walls 2 and 5 including the characters C and which are silvered as hereinbefore explained so as to convert these walls into mirrors over areas not occupied by the characters, or to the concave top walls 1 and 6 from which the light is reflected back again to the opposite wall carrying the characters C.

20 By such an arrangement the light which comes from various directions through the open top is reflected again and again until it is brought to the desired direction, viz. through the characters C.

25 Although advertising signs in the form of tubes or prisms have been shown, obviously these forms can be varied in shape in 30 various ways so as to attain the main object of the invention, viz. utilizing the whole light entering the open top by repeated reflection until finally the light passes through the 35 characters.

40 A device of the kind described is cheap to manufacture as all the walls formed from glass may be made in one operation and the silvering of all the walls may be done at one 45 and the same time, only the top wall being omitted from this process. In the same way to provide the contrasting ground on the device a black lacquer may be applied to the outside of the tube leaving only the top wall and the actual characters, and further, it 50 should be understood that the characters may themselves be covered with a coloured lacquer when it is desired to give the characters a colour, although this might also be attained by colouring the reflective surfaces of walls directing light through the characters.

55 Instead of forming the walls of a transparent material such as glass, the tubular casing forming the advertising device may be formed from material such as synthetic resin, celluloid, cellulose, gelatine, mica or other translucent or transparent material which lends itself to the manufacture of a device with the walls all integral with one another.

60 The method of manufacturing signs involving moulding or blowing a plurality of walls all integral with one another, may be also applied to a device wherein a silhouette or vignette is reflected.

The device may be completely tubular as herein described or substantially of channel section, for instance, by omitting the top wall.

65 Instead of forming a device, as herein described and illustrated, with the walls integral, a hollow advertising or like sign may be constructed to comprise a plurality of flat and/or curved panels which are capable of transmitting or diffusing light through the 70 areas occupied by the characters of the signs and of reflecting light from the contiguous areas, particularly when frosted glass is required to be utilized.

75 A device according to the invention may 80 include means such as a fitting in the top wall for the reception of an incandescent light so that the sign may be used at night time where diffused light is not available.

85 The characters of a sign, instead of being 90 on the reflecting wall, may be on a superimposed flexible transparent material, and conveniently passed over rollers so that the signs may be changed, e. g. the walls 8, Fig. 90 95 100 105 110 115 120 125 130 135 140 145 150 155 160 165 170 175 180 185 190 195 200 205 210 215 220 225 230 235 240 245 250 255 260 265 270 275 280 285 290 295 300 305 whereby the admitted light is virtually trapped within the device and controlled until it is constrained to emerge through the characters on the sign wall.

5 2. An advertising or like sign according to claim 1, comprising in combination with the reflectors contiguous to the light admission opening of the device, reflectors opposite the window connecting the lower part 10 of said side walls adapted to effect reflection to the walls carrying the sign characters of the admitted perpendicular light.

15 3. An advertising or like sign of the kind adapted to be illuminated by daylight constructed of open channel form comprising slightly diverging side walls, the upper parts of which converge towards one another and the bottom of the channel being deepest in the middle symmetrical to each side thereof, 20 the said walls and bottom carrying reflectors and one of the sides translucent sign characters.

25 4. An advertising or like sign adapted to be illuminated by daylight comprising, a frame like curved reflector bounding a light admission opening, reflecting side walls depending from said curved reflecting surface, and reflectors opposite said light admission opening connecting the lower part of said 30 side walls said side walls carrying the sign characters of the device, whereby the light admitted through the said frame like reflector is diffused through the sign characters.

35 5. An advertising or like sign adapted to be illuminated by daylight comprising a frame like reflector, opposed side walls depending from said reflector, reflectors on said side walls, translucent sign characters formed on said side walls, reflectors connecting the lower part of said side walls, the said reflectors co-operating to control the light admitted through the frame like reflector into the sign to constrain it to move through sign characters formed on said side walls.

45 6. An advertising or like sign according to claim 5, formed from a tube of transparent material whereby the frame like reflector, side walls and the reflectors connecting the lower part of said side walls are integrally formed, and metal plates closing the ends of the tube and formed for connection to suspending means.

55 7. A glass tube for use in making an advertising sign adapted to be illuminated by daylight, including side walls having translucent sign characters thereon, upper and lower walls, and a window intermediate the upper walls, permitting admission of light 60 into the tube, portions of said side walls and said upper and lower walls being opaque and reflecting, whereby light entering said window and not passing directly through said characters is reflected directly or indirectly to the side walls.

8. A glass tube for use in making an advertising sign, adapted for illumination by daylight, comprising seven facets, three at the upper portion of the tube including two outer opaque and reflecting facets, and an intermediate translucent top facet for admitting light into the tube, two bottom opaque reflecting facets, and two side facets having both opaque reflecting portions and translucent portions, the arrangement of the facets being such that light admitted through the window and striking the upper reflecting facets is directed to the opposite side facets, light striking the bottom facets is directed to the upper reflecting facets and thence to the side facets, and light striking the opaque portion of the side facets is directed to the opposite side facets.

15 9. An advertising or like sign adapted to be illuminated by daylight, comprising a glass tube including a translucent top wall and side walls, said side walls being converted into a mirror for internal reflection and having translucent portions carrying advertising characters, whereby advertisements on the side walls may be exhibited at one and the same time in opposite directions by illumination by daylight entering through the top wall.

20 10. A translucent tube for use in making an advertising sign adapted to be illuminated by daylight, including side walls for the sign characters and corresponding upper and lower walls and a translucent top wall connecting said upper walls intended for permitting the admission of light, the said side walls and corresponding upper and lower walls being designed so as to be adapted to form reflectors to reflect light entering the top directly or indirectly to the 25 side walls.

30 In testimony whereof I affix my signature.
GENNADY FRENKEL.
